UNITED STATES PATENT OFFICE.

CHRISTEN J. PETERSON, OF CHICAGO, ILLINOIS, ASSIGNOR TO WEARPROOF MAT COMPANY, OF CHICAGO, ILLINOIS, A CORPORATION OF ILLINOIS.

MAT.

1,090,791.

Specification of Letters Patent. Patented Mar. 17, 1914.

Application filed April 7, 1913. Serial No. 759,391.

To all whom it may concern:

Be it known that I, CHRISTEN J. PETERSON, a citizen of the United States, residing at Chicago, county of Cook, and State of Illinois, have invented certain new and useful Improvements in Mats, of which the following is a specification.

The present invention relates to that type of mat having a metal frame and employing, if desired, blocks of leather, creosoted wool-felt or other similar material and is used as a floor covering or protector.

The objects of the present invention are to arrange a series of pocket-like sections throughout the body of the mat which are produced by stamping or otherwise bending plate-like metallic strips and to provide a flange along the under side of said strips producing a relatively broad flat undersurface for the mat whereby any injury to the floor due to the cutting action of the thin strips of metal is eliminated, and whereby a broad foundation is given to the strips preventing their becoming bent because of torsional strains exerted during use.

A further object of the invention is to employ a flexible member as for instance a chain for connecting the pocket-like sections of the mat body whereby relative movement between said sections in a plurality of directions is permitted and thus the mat enabled to be folded into a compact form. And the invention further consists in the features of construction and combination of parts hereinafter described and claimed.

In the drawings: Figure 1 is a plan view of one form of mat made in accordance with the teachings of the present invention; Fig. 2 a section on line 2—2 of Fig. 1 looking in the direction of the arrow; Fig. 3 a plan view of another form of mat made in accordance with the teachings of the present invention; and Fig. 4 a view of the form of mat shown in Fig. 3 provided with a flexible connecting means for the mat sections.

Mats of the character to which the present invention relates are used as a protection for floors, and as a means for preventing slippage, and are generally made of series of foldable sections, each consisting of blocks of suitable flexible material bound on two sides by metal strips.

The present invention deals with a mat made for the purpose above stated, and in addition to employing metal strips which

extend only upon two sides of the blocks, it is also intended to so configure the strips as to form a series of pockets through the body of the mat which may bind all four sides by walls of metal when desired. A general objection to such a style of mat as previously made lies in the fact that the lower edge of the metal strips forming the pocket-like sections will cut or mar the floor, owing to the fact that the strips are necessarily of a relatively thin grade of metal and present a relatively sharp edge.

The principal aim and object of the present invention is to so configure these strips as to provide a relatively broad flat undersurface for the mat body, eliminating the objectionable cutting and scratching action heretofore stated, and this undersurface further provides a substantial and firm base for the sections so that said sections will not become twisted or bent out of shape by torsional strain which it may be subjected to during use, it being obvious that if the lower surface for the plates is in the nature of a thin edge it will present a bearing surface which would allow the plates to easily turn and bend under strain.

Referring now to the drawings and particularly to Fig. 1 the form of mat there shown consists of a series of metallic plate-like strips 5 which are bent throughout their length into a series of U-shaped sections 6, and as will be seen from the drawings each alternate U-shaped section will face in the same direction and each adjacent U-shaped section will face in a different direction. Each of the U-shaped sections 6, as will be seen, is of a slightly tapered nature so that the strips 5 when properly configured and joined together will to a certain extent nest within one another. This produces throughout the body of the mat a series of pocket-like sections 7, each surrounded on all four sides by a wall of metal.

The lower portions of the strip 5 are bent at right angles or approximately right angles to the body to provide flanges 8, thus creating throughout the undersurface of the mat a relatively broad flat bearing surface whereby no sharp edges are presented which might mar or scratch the floor, and whereby a firm, substantial base is given to the mat preventing any twisting by torsional strains during use. In the construction shown in Fig. 1 the flanges are slightly cut

away as at 9 to permit of a relative movement being had between the strips 5. The strips 5 as heretofore stated slightly nest or overlap and through the overlapping portions of said sections extends a rod 10 which connects the sections together and which forms a pivot about which the sections bend so as to permit the mat to be folded or rolled into compact form. Said rod is U-shaped initially, and when inserted through the sections has its unbent ends folded over to form the rod into the shape of a loop. If it is desired blocks 11 of leather, creosoted wool-felt or other material may be provided to give a cushioning and sound proof property to the mat, as well as giving increased frictional surface to the mat and intensifying the non-slippage feature.

20 Referring now more particularly to Fig. 3 of the drawing the form of mat there disclosed consists of a series of plate-like strips 12 bent into rectangular form creating a pocket-like member similar to all practical purposes to the pocket-like members 7 heretofore described, and the strips 12 are flanged at their lower portions as at 13 to provide a substantially broad, firm underfacing for the mat body, similar to the underfacing described in connection with the form of mat shown in Fig. 1. The pocket-like sections in this form of mat slightly overlap as will be seen from the drawing, and extending through said overlapping portions is a rod similar to the rod 10 previously described. In this form of device blocks of creosoted wool-felt or other substance may be inserted as described in connection with Fig. 1. The rods 10, both in 40 the form of mat shown in Fig. 1 and that shown in Fig. 3, may pass through the strips of creosoted wool-felt or other substance and serve as a binder for holding the same in place, suitable apertures of course being provided in said strips to permit the passage of the rods therethrough.

45 In Fig. 4 the same construction as to the pocketed member is employed as that described in connection with Fig. 3, but in place of using a rod to join the members together a flexible member as a chain 14 is employed thus permitting a folding of the

mat body in a plurality of directions so as to enable it to be folded into compact form. As will be seen by referring to Fig. 4 when 55 a chain or other flexible connection is employed the same is simply woven back and forth throughout the body of the mat.

In the case of the forms illustrated in Figs. 3 and 4, where each pocket-like member is separate and independent, any of the same may be removed for repair or substitution without destroying the efficiency of any other portion of the mat, or necessitating the removal or substitution of any 65 other than the portion or portions desired to be removed or substituted.

I claim:

1. A mat of the class described, comprising bent plate-like metallic strips, said 70 strips being flanged on their under side to provide a relatively broad flat metallic underfacing for the mat body and strengthening the mat against torsional strain and means for joining said strips together to 75 permit relative movement therebetween, substantially as described.

2. A mat of the class described, comprising a series of plate-like metallic strips each 80 bent to provide an independent pocket member, the lower portions of said strips being bent to provide a flange whereby a relatively broad flat metallic underfacing for the mat body is produced and the mat strengthened against torsional strains and means for 85 joining said members together to provide relative movement therebetween, substantially as described.

3. A mat of the class described, comprising a series of plate-like metallic strips each 90 bent to provide an independent pocket member, the lower portions of said strips being bent to provide a flange whereby a relatively broad flat metallic underfacing for the mat body is produced and the mat 95 strengthened against torsional strains and flexible means for joining said members together to permit relative movement therebetween in a plurality of directions, substantially as described.

CHRISTEN J. PETERSON.
